UNITED STATES PATENT OFFICE.

PHILIP MUELLER AND ANTON C. SCHUERMANN, OF DECATUR, ILLINOIS.

SANITARY DRINKING-FOUNTAIN FAUCET AND ROTARY SPOUT.

1,248,376.

Specification of Letters Patent. Patented Nov. 27, 1917.

Application filed March 24, 1916. Serial No. 88,529.

To all whom it may concern:

Be it known that we, PHILIP MUELLER and ANTON C. SCHUERMANN, citizens of the United States, residing at Decatur, in the 5 county of Macon and State of Illinois, have invented new and useful Improvements in Sanitary Drinking-Fountain Faucets and Rotary Spouts, of which the following is a specification.

- 10 This invention relates to improvements in fountain faucets of the type in which the delivery spout or discharge nozzle is adapted for use either as a faucet or as a sanitary drinking fountain.
- 15 Objects of our invention are to provide a fountain faucet through which the flow of water is controlled by the turning movement of the spout, the arrangement being such as to permit a restricted stream or gentle flow 20 of water to the fountain head or spout when the same is in one position, and a full flow or discharge of water when the spout is in position to be used as a faucet. Our device is simple in construction, efficient in 25 operation and consists of relatively few parts which may be readily assembled, and our improved fountain faucet may be used for a protracted period of time without wearing out or getting out of order.
- 30 The above and other objects of our invention are obtained by the structure described and claimed in the following specification and illustrated in the accompanying drawings, wherein—

35 Figure 1 is a vertical sectional view through a fountain faucet constructed in accordance with one embodiment of our invention, the spout being shown in full lines in position to be used as a drinking fountain 40 and in dotted lines for use as a faucet, the basin cock being shown partly in elevation.

Fig. 2 is a detail elevational view of the inner end portion of the rotatable spout.

Fig. 3 is a sectional view taken on line 45 3—3, Fig. 1.

Fig. 4 is a sectional view taken diametrically through the valve which controls the stream of water through the spout.

Fig. 5 is an elevational view of the valve. 50 Fig. 6 is a sectional view through a coupling nut.

Fig. 7 is a partial view of a drinking faucet partly in section disclosing another embodiment of the invention.

55 Fig. 8 is a sectional view taken on a longitudinal line through the coupling between

the rotary spout and the basin cock, and discloses another embodiment of the invention.

Fig. 9 is a sectional view through the sleeve against which the valve shown in Fig. 8 engages.

Fig. 10 is a fragmentary view through the end of the spout shown in Fig. 8.

Fig. 11 is a sectional view showing the valve construction disclosed in Fig. 8 in 65 position to permit a full or unrestricted flow of water to the fountain head or nozzle.

Referring to the drawings wherein like numerals indicate like parts in the several views, and particularly to the embodiment 70 shown in Figs. 1 to 6, 10 designates a valve body or basin cock which may be of any suitable construction, the same being here shown as provided with a valve 11 and a spring 12 about the stem of the valve to normally retain the valve upon its seat. The 75 basin cock 10 is preferably of a self-closing type, but, of course, the particular form of basin cock is immaterial as the same does not form part of this invention.

The basin cock is provided with a discharge branch or nipple 13 having an enlarged internal bore to receive a helical spring 14 adapted to engage at its inner end against the shoulder 14¹ provided by 80 said bore. The numeral 15 designates a movable plug or valve which controls the strength of the stream delivered to the rotary spout and which engages against the outer end of the helical spring 14. The stop 85 plug comprises in the present instance, a cylindrical body or disk 16 having disposed about its periphery projections or stops 17 preferably spaced apart at equal distances and these stops extend in one direction beyond the face of the disk as clearly shown in Fig. 4. The stop plug or valve is of sufficient diameter to fit snugly within the bore of the discharge nipple and is adapted to move bodily therein.

100 18 designates the discharge spout which carries at its outer end a suitable porcelain or other sanitary drinking fountain head or nozzle 19, and if desired, a suitable protecting ring or guard 20 may be provided. The 105 opposite or inner end of the spout 18 is provided with screw-threads 21 which as shown terminate somewhat short of the end of the spout and preferably they are of the quadrupole type, so that upon rotary movement of the spout the latter will move longitudinally at a relatively rapid rate.

Through the wall of the spout at the end thereof is a notch or groove 22.

The spout 18 is connected to the basin cock 10 by means of a coupling nut 23 having a through opening, which opening intermediate its ends is somewhat reduced in diameter and which is provided with screw-threads corresponding to the complementary screw-threads 21 adjacent to the end of the 10 spout. At one end of the coupling nut 23 is an enlarged bore 24 internally screw-threaded to receive complementary external screw-threads on the outer end of the discharge nipple 13. At its opposite end the 15 nut is provided with an inner bore 25 slightly larger in diameter than the intermediate portion of the opening, and a somewhat larger outer bore 26.

The spout has a circumferential flange or 20 collar 27 of sufficient diameter to fit in the inner bore 25 in which it is adapted to move back and forth, the rotary movement of the spout being limited by the collar striking the shoulder 25' at the inner end of said bore.

25 Fitting within the recess or outer bore 26 between the shoulder 26' and a packing ring 29 is a metal washer 28 which is adapted to be forced into place by a flanged nut 30 to provide a fluid-tight joint between the coupling nut 23 and the spout 18, the flanged nut being screw-threaded over the end of the coupling nut 23 and embracing the spout for retaining the washer and packing in place.

30 When the head or nozzle 19 of the spout is in position to be used as a drinking fountain, as shown in full lines in Fig. 1, the end of the spout engages against the outer surface of the disk portion 16 of the stop 35 valve or plug 15, and the water, the basin cock 10 being operated to admit the same, can pass from the discharge opening in the nipple 13 into the spout through the groove or notch 22 only, and, therefore, a restricted 40 flow or gentle stream is delivered to the fountain head.

When the spout is swung downwardly into the position shown in dotted lines, Fig. 1, so that it may be used as a faucet, the spout moves longitudinally and outwardly, and this movement is fairly rapid as the threads 45 21 are of considerable pitch. The stop plug or valve 15, due to the spring 14 moves with the spout until the ends of the stops 17 engage the shoulder 24' provided at the inner 50 end of the bore 24 of coupling nut 23, the end of the spout then moving away from the face of the plug, so that the water after flowing around the valve 11 and into the nipple 55 13 passes around the stop valve 15 by means of the notches or passages between the stops 17, and as the inner end of the spout is withdrawn from the face of the stop valve the full force of the stream may pass into the 60 65 spout. The outward movement of the

spout is of course limited by means of the washer 28.

In the embodiment of our invention illustrated in Fig. 7 a stationary valve is shown which is used in place of or as a substitute 70 for the slideable or movable valve 15 disclosed in the embodiment heretofore described. In the embodiment shown in Fig. 7, the construction of the coupling nut 23 and the spout 18 corresponds to like parts 75 in the preceding embodiment, the inner end of the spout being provided with the notch 22 to permit a restricted flow of water to the fountain head or stream outlet when the spout is in proper position. The discharge 80 opening in the nipple 13 is substantially of the same diameter throughout, and at the outer end of the nipple is an annular recess 31 which receives the stationary stop valve 85 or washer 32. This valve is positioned between the shoulder 33 formed by the recess 31 and the shoulder 24' at the inner end of the bore 24, and preferably the thickness of the valve 32 is slightly less than the depth of the recess 31 to permit the shoulder 24' to 90 fit tightly against the outer edge of the nipple 13 and thus make a fluid-tight joint. The valve 32 has a plurality of perforations or openings 34 therethrough disposed adjacent its periphery and which register with 95 the discharge opening in the nipple 13, but which do not register with the passageway in the rotary spout 18.

When the spout 18 of Fig. 7 is in position to be used as a drinking fountain, that 100 is, in the position shown in this figure, the inner end of the spout abuts against the outer face of the stationary stop valve 32 and thus the flow of water is limited to that which passes through the notch 22, and a 105 restricted stream is provided for at the bubbling head 19. When the spout is rotated, so that the fountain head or nozzle 19 extends downwardly, the spout moves longitudinally outward, so that the inner end of 110 the same is withdrawn from engagement with the face of the stop valve and an unrestricted or full flow of water then passes through the perforations 34 in the stationary stop valve 32 and between the inner end 115 of the spout and the valve 32 to the nozzle 19.

In the embodiment of our invention shown in Figs. 8 to 11, the stop valve is carried by the inner end of the spout 18 and is movable therewith. In these figures 35 120 designates an open-ended sleeve having a base or flange 36 which is clamped into place between the end of the nipple 13 and the shoulder 24' of the coupling nut 23, as shown. The rotary spout 18 at its inner end 125 is of reduced diameter and is adapted to telescope into or slide through the sleeve 35. The inner end of the rotary spout 18 has fixedly secured thereto a stop valve 37 which is of somewhat larger diameter than 130

the outer diameter of the rotary spout, so that an outwardly extending flange 38 is provided which may be brought into engagement with the inner end of the open-ended sleeve 35. In Figs. 8 and 9, the sleeve has a restricted notch or opening 39 which admits of the restricted flow of water through the spout when the stop valve is in engagement with the inner end of the sleeve; while in Fig. 11, the restricted stream or bubbling head opening 40 passes through the body of the valve 37. The spout at its inner end has a plurality of openings 41 which serve as inlets to the interior of the spout. The threads 21 on the spout 18 are, in the present instance, left-handed instead of right-handed, so that when the spout is rotated to swing the head or nozzle 19 into a downwardly extending position, the spout moves longitudinally inward toward the basin cock 10, and the flange 38 of valve 37 is moved from engagement with the seat provided by the inner end of the open-ended sleeve 35, and an unrestricted stream of water is obtained.

It will be noted that in each of the embodiments herein disclosed, the spout 18 when rotated moves longitudinally and thereby controls the strength of the flow of water to the stream outlet in the head 19, a gentle flow being obtained when the spout is in position for use as a drinking fountain, and a full or unrestricted flow of water being provided for when the head is turned downwardly for use as a faucet. In each case, a valve head and a valve seat are provided, and these members are moved relative to one another when the spout is moved longitudinally. In the embodiments shown in Figs. 1 to 6, and Fig. 7, the inner end of the spout 18 which is adapted to abut or engage against the face of the stop valve or head 15 or 32, as the case may be, constitutes the valve seat which moves to and from the stop valve, while in Figs. 8 to 11, the inner end of the open-ended sleeve 35 constitutes a stationary valve seat, and the stop valve or head 37 carried on the inner end of the spout moves into and out of engagement therewith upon rotation of the spout.

It will further be noted that in each of the embodiments of this invention the construction is such that when the spout is rotated from one position to another it is always positively stopped in a correct position, to be used either as a drinking fountain or as a faucet. In Fig. 1 the outward movement of the spout is limited by the collar 27 engaging the washer 28, and its inward movement by the collar 27 striking the shoulder 25'. In Fig. 7 the outward movement of the spout is limited by the collar 27 striking the washer 28, and the inward movement of the spout is controlled due to the engagement of the inner end of

the spout against the stationary valve 32, while in Fig. 8 the collar 27 abuts the shoulder 25', and the valve head 37 engages the end of the sleeve 35 to limit the inward and outward movements respectively of the spout.

It is, of course, obvious that our invention is susceptible of various modifications and changes which would be within the spirit of our invention without departing from the scope of the following claims.

What we claim is:—

1. In combination, a body having a discharge opening, a second body having a port in communication with the discharge opening in the first body, one of said bodies having simultaneous rotary and longitudinal movement relative to the other, valve means therebetween controlled by the relative longitudinal movement of the body and permitting an unrestricted flow of water when the bodies are in one position, and means for permitting a restricted flow of water when the bodies are in another position.

2. In combination, a body having a discharge opening, a valve head, a valve seat and a rotary pipe carrying one of said members, and when in one position retaining said valve members in contact, a passage or port to permit a restricted flow of water through said pipe when said valve members are in contact with each other, and means to move said pipe rectilinearly when the same is rotated for moving said valve members apart to permit an unrestricted flow of water through the pipe.

3. In combination, a body having a discharge opening, a valve head, a valve seat, a rotatable pipe carrying one of said valve members, means in one of said valve members to permit a restricted flow of water through said pipe when the valve head is on its seat, and means to move said pipe rectilinearly when rotated for withdrawing the valve member carried thereby from the other valve member to permit an unrestricted flow of water through the pipe.

4. In combination, a body having a discharge opening, a valve head, a valve seat, a rotatable pipe carrying one of said valve members, a passage in one of said valve members to permit a restricted flow of water through said pipe when the valve head is on its seat, and means to move said pipe rectilinearly when rotated for withdrawing the valve member carried thereby from the other valve member to permit an unrestricted flow of water through the pipe.

5. In combination, a body having a discharge opening, a valve in said opening, a rotatable pipe adapted to engage at its inner end against the face of said valve, means to permit a restricted flow of water through said pipe when the end of the same is engaging said valve, and means to move said

pipe rectilinearly when the same is rotated for withdrawing said end of the pipe from said valve to permit an unrestricted flow of water.

- 5 6. In combination, a body having a discharge opening, a valve in said opening, a rotatable spout adapted to be turned into one position to be used as a drinking fountain and into another position to be used as 10 a faucet, said spout being adapted to engage at its inner end against the face of said valve, a passage to permit a restricted flow of water through said pipe when the end of the same is engaging said valve, and 15 means to move said pipe rectilinearly when the same is rotated for withdrawing the end of the pipe from said valve to permit an unrestricted flow of water.

7. In combination, a body having a discharge opening, a spring in said opening, a valve in said opening normally pressed outwardly by said spring, a rotatable pipe adapted to engage at one end against said valve and having a notch or passage in said 25 end to permit a restricted flow of water through said pipe when the latter is in one position, a connecting member between said member and pipe, and means for moving said pipe rectilinearly when the same is 30 rotated for withdrawing the end of said pipe from said valve to permit an unrestricted flow of water through said pipe.

8. In combination, a body having a discharge opening, a valve member in said discharge opening, a rotatable pipe member 35 adapted to engage at its inner end against said valve member, a passage in one of said members to permit a restricted flow of water when said pipe member is in engagement 40 with said valve member, a coupling nut between said body and pipe member, and screw-threads between said coupling nut and pipe member for moving said pipe member rectilinearly when the same is rotated to withdraw 45 the inner end of said pipe member from said valve member to permit an unrestricted flow of water through said pipe member.

9. In combination, a body having a discharge opening, a valve in said discharge opening, a rotatable pipe adapted to engage at its inner end against said valve, a passage between said valve and pipe to permit a restricted flow of water through said 55 pipe when the end of the pipe is in engagement with said valve, a coupling nut between said body and pipe, a spring in said discharge opening normally pressing said valve toward said rotatable pipe, means between 60 said coupling nut and pipe for moving said pipe rectilinearly away from said valve when the pipe is rotated to permit an unrestricted flow of water therethrough, and means for limiting the movement of said

valve when said pipe is withdrawn therefrom. 65

10. In combination, a body having a discharge opening, a valve in said opening adapted to move bodily therein, a rotatable spout adapted to engage at its inner end 70 against the face of said valve, a passage to permit a restricted flow of water through said spout when the inner end of the same engages said valve, a nut for connecting said body and spout, screw-threads between said 75 nut and spout for permitting longitudinal movement of said spout when the same is rotated to withdraw the inner end of the spout from said valve and thus allow an unrestricted flow of water through said 80 spout, and means on the nut for limiting the outward movement of said valve to allow the inner end of the pipe to be withdrawn therefrom.

11. In combination, a body having a discharge opening, a rotatable spout adapted to be turned into one position to be used as a drinking fountain and into another position to be used as a faucet, a connection between said body and spout, a valve in said 85 opening adapted to engage against the inner end of said rotatable spout when the same is in position for use as a drinking fountain, said spout having a passage or notch at its inner end to permit a restricted flow of 95 water when the same is used as a drinking fountain, and screw-threads between said connection and spout to move said spout rectilinearly away from said valve when the same is rotated into position for use as a 100 faucet to permit an unrestricted flow of water therethrough.

12. In combination, a body having a discharge opening, a rotatable spout adapted to be turned into one position to be used as a 105 drinking fountain, and in another position to be used as a faucet, a connection between said body and spout, a valve head carried by said body or spout, a valve seat carried by the other member, said head and seat being brought into engagement with each other when the rotatable spout is in position for 110 use as a drinking fountain, and means to move said spout rectilinearly and said valve members apart when the spout is rotated into position for use as a faucet to permit an unrestricted flow of water therethrough.

13. In combination, a basin cock having a nipple with a discharge opening, a rotatable spout having a drinking head adapted 120 to be turned into one position for use as a drinking fountain and into another position to be used as a faucet, a valve head carried by one of said members, a valve seat carried by the other of said members, a passage or notch through one of said members to permit a restricted flow of water when the valve head is upon its seat, and means 125

between the nipple and the spout to move the spout rectilinearly when the same is rotated into position for use as a faucet thereby causing relative movement between the 5 head and seat to permit an unrestricted flow of water to the drinking nozzle.

14. In combination, a body having a discharge opening, a rotatable spout adapted to be turned into one position to be used as 10 a drinking fountain and in another position to be used as a faucet, a connection between said body and spout, a valve head and a valve seat, one of said members being carried by said spout, said head and seat being 15 brought into engagement with each other when the rotatable spout is in position for use as a drinking fountain, means to move said spout rectilinearly and said valve members apart when the spout is rotated into position 20 for use as a faucet to permit an unrestricted flow of water therethrough, and means for limiting the rectilinear movement of said spout to stop the same in proper positions.

25 15. In combination, a body having a discharge opening, a rotatable spout adapted to be turned into one position to be used as a drinking fountain and in another position to be used as a faucet, a connection between 30 said body and spout, a valve head carried by said body or spout, a valve seat carried by the other member, said valve head and seat being brought into engagement with each other when the rotatable spout is in

position for use as a drinking fountain, 35 means for moving said spout rectilinearly and said valve members apart when the spout is rotated into position for use as a faucet to permit an unrestricted flow of water therethrough, and a collar on said 40 spout adapted to engage said connecting member to limit the rectilinear movement of said spout.

16. In combination, a valve body member having a discharge opening, a rotatable 45 spout member adapted to be turned into one position to be used as a drinking fountain and into another position to be used as a faucet, a valve head carried by one of said members, and a valve seat carried by the 50 other member, said head and seat being brought into engagement with each other when the rotatable spout member is in position for use as a drinking fountain, said spout member moving rectilinearly, and said 55 valve members being moved apart when the spout member is rotated into position for use as a faucet to permit an unrestricted flow of water therethrough.

In testimony whereof we have hereunto 60 set our hands in presence of two subscribing witnesses.

PHILIP MUELLER.
